CONTROL SYSTEM

David R. Shoultz, Scotia, N. Y., assignor to General Electric Company, a corporation of New York

Application March 30, 1933, Serial No. 663,527

8 Claims. (Cl. 164—68)

This invention relates to control systems, more particularly to systems for controlling the operation of machines having an element operating on a strip of material, and it has for an object the provision of a simple, reliable and efficient control system of this character.

More specifically the invention relates to systems for controlling the operation of machines in which an element is required to operate in predetermined relationship with the strip of material, such for example as machines for cutting a strip of material into bag lengths or package wrapper lengths in register with designs, labels or other matter previously printed on the strips.

In machines of this character which usually consist of a rotary cutting knife and a pair of rolls for feeding the strips to the knife, it is difficult to maintain the cuts in proper register, even with exactly calculated gear ratios because of variable factors such as slippage, and stretch or shrinkage of the strips due to varying moisture conditions of the atmosphere. These variables are cumulative so that each successive cut is made with greater error. In case the cut is not being made in proper register, it is necessary to compensate for the error.

The present invention is an improvement of the invention disclosed in U. S. Patent No. 2,002,374, William R. King, filed May 30, 1930 and is also an improvement on the invention disclosed in application Serial No. 589,757, Austin L. Whiteley, filed January 29, 1932; and on the invention disclosed in my prior application Serial No. 623,795 filed July 21, 1932. These applications and the King patent are all assigned to the assignee of the present invention, and the inventions thereof were all made prior to the date of the present invention.

A further and more specific object of this invention is the provision of means for eliminating hunting, i. e., continued alternate cutting of the strip on opposite sides of the successive desired points of cut-off.

In carrying the invention into effect in one form thereof, a variable speed driving connection is provided between the feeding means and the operating element, and a lever is provided for operating on the variable speed connection, together with means for moving the lever so as to effect a relatively large correction for the space or positional relationship of the strip and the element, and means for subsequently reducing the amount of movement of the lever to provide a relatively small correction for the speed relationship of the strip and operating element. In

a specific embodiment of the invention, the strip is provided during the printing process with index markings in predetermined relationship with the labels or other printed matter, and suitable light sensitive means controlled by these index markings function through suitable control apparatus to energize an electric motor and cause the latter to move the lever which operates on the variable speed connection and thereby introduce the relatively large correction for the space relationship of the strip and operating element, and subsequently centering springs attached to the lever reduce the amount of this correcting movement under the control of a calibrated time delay device, so as to make an ultimate or final correction for the relative speeds of the strip and the operating element.

In illustrating the invention in one form thereof, it is shown as embodied in a system for controlling the cut-off operation of a bag cutting or package wrapper cutting machine, but it will be understood that this application of the invention is shown merely for the purpose of illustration and that the invention may be utilized generally for controlling machines having an element for performing various operations on a strip of material in predetermined register with designs, labels, or other matter on the strips.

For a better and more complete understanding of the invention, reference should now be had to the following specifications and to the accompanying drawing in which Fig. 1 is a simple diagrammatic representation of an embodiment of the invention and Fig. 2 is a simple diagrammatic representation of a modification.

Referring now to the drawing, a strip of material 10, such for example as a material from which bag lengths or package wrapper lengths are to be cut, is fed from a supply roll (not shown) over a table 11 to an element of the machine operating thereon, such as that represented by the rotary cutting knife 12. Means illustrated as comprising a pair of rolls 13 are provided for feeding the strip to the cutting element 12. The strip 10 is provided with designs, labels, or other printed matter (not shown) at each section, such for example as the section of the strip between the broken line 14 and a similar line obscured by the cutting element 12, at which lines it is desired to sever the strip for the purpose of forming articles such as package wrapper lengths or bag lengths upon which the design, label or other matter is properly centered.

The feed rolls 13 are driven by any suitable driving means, such for example as that repre-

sented by the electric motor 15 to the drive shaft of which the shaft of the rolls 13 are mechanically connected by gearing 16. As shown, the motor 15 is supplied from a suitable source of power, such for example as that represented by the upper and lower supply lines 17 to which the motor is connected by means of the conductors 18. A motor starting device 20 of any suitable type is included in circuit with the motor.

10 Likewise the rotary cutting knife 12 may be driven by any suitable driving means, the speed of which may be varied or adjusted to provide for adjustment of the relative operating speeds of the knife and the moving strips so as to cause 15 the knife to operate in a predetermined relationship with respect to the sections of the strip, i. e., to sever the strip at the predetermined cut-off lines 14. Preferably, however, the cutting knife 12 is driven by the same driving means as 20 those employed to drive the feed rolls 13 and in the drawing, the knife 12 is shown as being driven by the electric motor 15 through a variable speed connection 21, illustrated as a variable speed transmission device comprising a 25 pair of cone pulleys 22 and 23, connected together by a belt 24, the position of which upon the surfaces of the pulleys is varied by means of a belt shifting device 25. The pulley 22 is fixedly mounted on the drive shaft of the motor 15 for 30 rotation therewith and the pulley 23 is mounted upon the shaft of the cutting knife 12 so as to rotate therewith.

The belt shifter 25 is actuated by means of a lever 26 to one extremity of which it is connected 35 by means of a connecting link 27. As shown, the lever 26 is provided with a central collar portion 26a, which is pivotally connected to a nut 27, which in turn is actuated in one direction or the other along the screw 28 when the latter is rotated. The lever 26 is fulcrumed in a bifurcated 40 member 30 which as shown is attached by means of connecting rod 31 to the plunger 32 of a retarding device illustrated as an oil dashpot 33. Centering springs 34 and 35 serve to center the 45 lever 26 with respect to the nut 27 and in so doing they effect movement of the fulcrum point 30.

This lever arrangement serves to provide a correction in the space relationship between the desired cut-off points of the strip 10 and the 50 blade of the rotary cutting knife 12 when such is necessary, and also serves to effect the necessary correction for the relative speeds between the strips and the cutting knife. Under normal operating conditions the lever 26 occupies the 55 upright position in which it is illustrated. If the strip 10 becomes out of register with the knife 12, the nut 27 is advanced along the screw 28 in the proper direction which effects a movement of the lever 26 about the fulcrum point 30. This movement of the lever effects a relatively large temporary change in the relative speeds of the strip 10 and the knife 12 to compensate for the positional relationship of the strip and the knife. Subsequently the centering springs 34, 35 reduce 60 the amount of movement of the lever 26 by moving the lever 26 in the opposite direction. This last mentioned movement of the lever 26 of course changes the position of the original fulcrum point 30 and this movement takes place at a speed determined by the adjustment of the dashpot 33. In its final position the lever 26 is again substantially upright as illustrated, and displaced along the screw 28 by an amount proportional to the rotation thereof, thus providing a small and rela-

tively permanent change in the relative speeds of the strip and cutting knife 12.

As shown the screw 28 is rotated by a small pilot motor 36 to the driveshaft of which the screw is connected through suitable worm reduction gearing 37. The pilot motor 36 is provided with a split series field winding comprising the two oppositely wound portions 36a and 36b. Energization of the motor through one or the other of these portions of the winding effects operation of the motor in one or the other directions in a well understood manner.

Energization of the pilot motor 36 through one or the other of the oppositely wound portions of its split field winding is controlled by suitable electromagnetic switching mechanism illustrated as a pair of contactors 38 and 40. The directional contactor 38 when actuated to its upper position serves to connect the pilot motor 36 to a suitable source of power, represented by the two supply lines 41, in series relationship with the portion 36b of its field winding to effect rotation of the motor in a given direction, for example, the forward direction. Similarly operation of the contactor 40 to its upper position connects the pilot motor 36 to the source 41 in series relation with the portion 36a of its field winding.

As shown in the drawing, the sheet 10 is provided at suitable intervals with indicia or index markings shown as black spots 42 which are preferably printed upon the strip when the design, label or other matter is printed thereon. These spots are all positioned on the strip in a predetermined relationship with respect to the printed matter, or with respect to the cut-off lines 14. No particular relationship between the position of the index markings and the cut-off lines is necessary since it is only required that the same relationship obtain between each of the markings and the printed matter or cut-off line with which it is associated.

The operation of the pilot motor 36 to effect the desired correction between the strip 10 and the cutting knife 12 is automatically controlled by 45 means of the control system illustrated in the drawing as comprising a light sensitive device 43, preferably a photoelectric cell, which responds to the passage of the index marks 42 and a cooperating selector switch 49 controlled in accordance 50 with the position of the rotary knife 12 to energize one or the other of the electric valves 44, 45 in the respective output circuits of which the operating coils of the contactors 38 and 40 are connected. As shown, the light sensitive device 55 43 is mounted above the strip 10 and in such a position with respect to a source of light 46 as to be influenced by the beam of light reflected from the strip. The light source 46 is illustrated as an ordinary incandescent lamp suitably mounted 60 above the strip and supplied with energy from a suitable source such for example as that represented in the drawing by the supply lines 17 to which the lamp is connected by means of the conductors 47. The light sensitive device 43 is so 65 positioned with respect to the rotary knife 12 that one of the index marks 42 interrupts the beam of reflected light to the light sensitive device when one of the cut-off lines of the strip 10 is in some predetermined position, for example, 70 when it is at the point of cut-off on the table 11. When one of the index markings 42 is in the position shown with respect to the light source 46 and the light sensitive device 43 shown in the drawing, the beam of light reflected from the strip to 75

the light sensitive device 43 is interrupted or at least is greatly diminished, and this interruption or diminution of the received beam of light causes the light sensitive device 43 to produce a controlling impulse, i. e., a change in the magnitude of the current flowing in the electrical circuit 48 in which it is connected.

Since the impulses produced in the electric circuit 48 when dark spots diminish the light received by the light sensitive device are very feeble, it is necessary to amplify these impulses in order that they may be transmitted and utilized to control the energization of the electric valves 44 and 45. Accordingly, a suitable amplifying device 50 is interposed in the circuit between the light sensitive device 43 and the electric valves 44, 45, and this amplifying device is connected to a suitable electrical source by means of conductors 51.

Although the electric valves 44 and 45 may be of any suitable type, they are preferably of the three electrode type. As illustrated, the valves 44 and 45 are respectively provided with cathodes 44a and 45a, grids 44b and 45b and plates or anodes 44c and 45c. These valves are also preferably of the type having a small quantity of an inert gas such for example as mercury vapor introduced into their envelopes after exhaust. The presence of this gas within the envelope serves to convert the usual pure electron discharge into an arc stream, the starting of which is controlled by applying a suitable positive bias to the grid and thus constituting the valves electrostatically or grid controlled arc rectifiers. Once current has started to flow in the anode circuit of this type of valve, it cannot be stopped by control of the grid voltage, but can only be stopped by interrupting the anode circuit or reducing the anode voltage substantially to zero.

The anodes 44c and 45c are respectively connected with the positive side of the direct current source 41 in series relationship with the respective operating coils of the directional contactors 38 and 40. Although the controlling impulses produced by the passage of the index marking 42 beneath the light sensitive device 43 are of extremely brief duration, they are nevertheless sufficient to initiate the flow of current in the anode circuit of the electric valve, which current continues to flow until the anode circuit is interrupted. A suitable switching device 52 having a magnetic circuit designed to provide a time element in its drop out operation serves to interrupt the anode circuit of the electric valves 44 and 45 a predetermined interval of time after the flow of anode current is initiated. Cathodes 44a and 45a of the valves are connected to the negative side of the supply source 41 by means of the conductor 53 with the result that the anodes 44c and 45c are positively biased with respect to the cathodes, and as shown, the grids 44b and 45b are respectively connected to segments of the selector switch 49 which in turn are respectively connected to sectors 49a and 49b insulated from each other as illustrated and upon the periphery of which bears a brush 54 connected through the conductor 55 and amplifying apparatus 50 to the circuit of the light sensitive device 43. The selector switch 49 is so arranged on the shaft of the rotary knife 12 that the brush 54 is in contact with the insulating portion between the sectors 49a and 49b at the instant that the index mark 42 interrupts the beam of light reflected from the strip to the light sensitive device 43 provided, however, that the rotary knife 12 is in such a re-

lationship with respect to the strip as to sever it at the proper point of cut-off. Thus it will be seen that when the knife 12 is in correct register with the printed matter on the strip 10, the passage of the index marks 42 to interrupt the light beam received by the light sensitive device 43 does not cause any impulses to be transmitted to the grids 44b and 45b of the electric valves.

With the above understanding of the elements and the apparatus and their organization in the completed system, the operation of the system itself will readily be understood from the following detailed description.

The system is placed in operation by closing the switch 56 to complete an energizing circuit 15 for the operating coil of the time element device 52 which circuit is readily traced from the positive side of the supply source 41 through the coil of the time element device 52, the lower contacts of contactors 40 and 38 in their lower positions and thence to the negative side of the supply source 41. The time element device 52 in responding to the energization of its coil is operated to its upper or closed position in which its contact connects the anodes 44c and 45c to the positive side of the supply source 41. The driving motor 15 is started by the starting device 20 and thereafter the feed rolls 13 feed the strip 10 to the rotary knife 12 at the required rate. As long as the necessary predetermined relationship exists between the rotary knife and the printed matter on the strip 10, the index markings 42 interrupt the light beam received by the light sensitive device 43 at the instant that the brush 54 bears upon the insulated portion of 35 the selector switch 49 and no correcting action is made.

In case the cut is not being made in register with the printed matter on the strip, it is necessary to make a correction in the space relationship between the rotary knife and the strip and it is also necessary to alter the velocity relationship of the rotary knife and the feed rolls to compensate for the error which first caused the knife to become out of register with the strip. Assume for example, that due to some cause the knife becomes out of register with the printed matter on the strip so that the cut is made after the cut-off line has passed the point at the table at which the cut is made. That is to say, the knife is cutting late. The brush 54 is in contact with the sector 49a at the instant that an index mark 42 interrupts the beam of light received by the light sensitive device and thus an impulse is transmitted through the circuit 48 to the amplifying apparatus 50, which in turn causes a positive bias to be applied to the grid 44b of the electric valve 44. The positive bias applied to the grid of the valve 44 initiates the flow of current in the anode circuit of the electric valve 44, thereby energizing the operating coil of the contactor 40 which in responding to the energization of its coil is operated to its upper position to connect the armature winding 65 of the pilot motor 36 to the supply source 41 in series relationship with the split field winding portion 36a. The index mark 42 immediately passes out of cooperative relationship with the light source 46 and light sensitive device 43, but 70 as previously pointed out the flow of current in the anode circuit of the electric valve is maintained until the anode circuit is interrupted. Consequently the contactor 40 remains operated to its upper position and the motor 36 remains 75

energized. The motor 36 rotates the screw 28 in a direction such that the nut 27 is displaced along the screw to the left, as indicated by the arrow. This displacement is comparatively rapid so that the bifurcated member 30 becomes the fulcrum of the lever 26 thereby resulting in a comparatively rapid movement of the belt shifter 25 in a direction such as to increase the speed of the knife 12 with respect to that of the feed 10 rolls 13. The effect of this rather sudden and large movement of the belt shifter 25 is to provide a rather large temporary correction for the positional relationship of the knife and the strip. It will be seen, however, that if the knife 12 continued to rotate at this substantially increased speed, it would soon become ahead of the strip and would be cutting early instead of late. However, after an interval of time determined by the constants of the time element device 52, the 20 contact of the latter due to the deenergization of its operating coil by the upward movement of the contactor 40, descends to its lower position and interrupts the anode circuit of the electric valve 44 with the result that the operating coil 25 of contactor 40 is deenergized. Contact 40 in responding to the deenergization of its coil descends to the lower position in which it is illustrated and disconnects the motor 36 from the source 41.

30 When the lever 26 was rotated in a counter clockwise direction about the fulcrum point 30, the spring 34 was tensioned and similarly the spring 35 was placed under compression. These 35 tensional and compressional forces naturally tend to rotate the lever 26 in the opposite direction, i. e., these forces tend to rotate the lever 26 in a clockwise direction. The pins by which the collar 26a is attached to the nut 27 now become the fulcrum of the lever 26 and the clockwise rotation of the lever takes place at a speed determined by the adjustment of the dashpot 33. It is seen that as the clockwise rotation of the lever 26 takes place, the previous fulcrum 30 is moved in the left-hand direction and this movement continues until the centering springs 34 and 35 move the lever 26 into the upright position in which it is illustrated. It is observed that the clockwise rotation of the lever 26 is opposite to the movement of the lever produced 40 by the motor 36 so that the belt shifter 25 is moved in the right-hand direction to decrease the speed of the knife 12 relative to the roll 13. Thus the relative large change in speed of the knife 12 is considerably reduced. However, the 45 belt shifter 25 is not moved completely back to the position it occupied prior to the initiation of the correcting action, but on the contrary is moved to the position it would have occupied had the dashpot 33 and the bifurcated member 50 30 not provided a fulcrum for the lever 26. Thus finally the lever 26 and the belt shifter 25 come to rest in a position differing from their initial position prior to the initiation of the correcting action by an amount proportional to the travel 55 of the nut 27. This amount is just sufficient to compensate or correct the speed of knife 12 with respect to the strip for the initial error in their relative speeds which initiated the correcting action. This last mentioned correction, i. e., correction 60 for the relative speeds of the knife and the strip is much smaller than the temporary correction for the positional relationship and this correction is permanent or relatively permanent in that it endures until the strip and knife have again become out of register and a new correc-

tion is made. Thus the equipment provides a rather large temporary correction and a much smaller permanent correction. As pointed out earlier in the specification, this is the condition that is necessary for stability and the elimination of hunting in a system of this character. 5

If the rotary knife 12 becomes out of register with the strip 10 so that the cut is made early instead of late, the brush 54 is in contact with the sector 49b at the instant that the index 10 marking 42 passes beneath the light sensitive device 43, thereby causing a positive bias to be applied to the grid of the valve 45 and in turn energizing the directional contactor 38. Contact 38 in responding to the energization of its 15 coil moves to its upper position in which it interrupts the energizing circuit of the time element device 52 and in which it connects the pilot motor 36 to the source 41 in series relationship with the portion 36b of its split field winding, 20 thereby causing this motor to rotate in a direction opposite to that previously described, and causing relative space and relative speed correction between the knife 12 and the strip 10 to be made in the opposite sense to the corrections 25 previously described for the condition in which the knife was cutting late.

In the modification of Fig. 2 the belt shifter 60, the lever 61, the lever operating motor 62, and the time element device 63 are in all respects 30 similar to Fig. 1. Similarly the light sensitive device, amplifying apparatus, selector switch and electric valve apparatus, which for the purpose of simplicity and avoidance of repetition are omitted from the drawing, are in all respects 35 identical with the apparatus already described in connection with Fig. 1. The system of Fig. 2 differs from that of Fig. 1 primarily in that the dashpot connected to the lever is replaced by two solenoids 64 and 65. These solenoids are 40 attached to the lever 61 near the point where the centering springs 66 and 67 are attached. The contactors 68 and 70 are similar to the contactors 38 and 40 of Fig. 1, but it will be observed that they are provided with additional upper 45 auxiliary contacts 71 and 72 respectively whereby selective energization of the contactors 68, 70 effects selective energization of the solenoids 64, 65. It will be observed that the solenoids 64 and 65 are attached to the lever 61 so that they 50 act in opposition. Thus when one or the other of these solenoids is energized the lever 61 is rotated in a corresponding direction about the fulcrum 73.

In operation, when the strip and the knife become out of register, one or the other of the contactors 68, 70 is energized and operated to its upper closed position in a manner similar to that described in connection with the operation of Fig. 1. Assuming that the contactor 68 is 60 energized, its upper auxiliary contact 71 completes an energizing circuit for the operating coil of solenoid 64 that is traced from the positive side of the supply line 74, conductors 75 and 76, upper contacts of contactor 68, operating coil 65 of solenoid 64 and thence by conductors 77 and 78 to the negative side of the supply line 74. Simultaneously the lower contacts of the contactor 68 in its upper position connect the motor 62 to the source 74 over a circuit that is traced 70 from the positive side of the supply line 74 through conductors 75 and 76, lower contact of contactor 68 in the upper position thereof, split field winding 62a, armature winding of motor 75

62 and thence by conductor 78 to the opposite side of the supply source 74. In response to the energization of its operating coil the solenoid 64 rotates the lever 61 in a clockwise direction thereby producing the comparatively large movement of the belt shifter 60 and the large temporary correction for the positional relationship of the strip and the cutting knife. Simultaneously the motor 62 rotates the screw in such a direction that the nut is displaced along the screw in a direction toward the right, as indicated by the arrow. This produces the slight additional correction for the relative speed of the strip and the knife. The clockwise rotation of the lever 61 places the spring 67 under tension and the spring 66 under compression and these forces of course tend to restore the lever 61 to its original upright position.

The operation of the contactor 68 to its upper position also deenergizes the operating coil of the time element device 63 so that after an interval of time determined by the constants of the time element device, its contact descends to the lower position in which it is illustrated, and in which it interrupts the energizing circuit for the operating coil of the contactor 68. As a result of its deenergization the contactor 68 descends to the lower position in which it is illustrated, thereby deenergizing both the solenoid 64 and the motor 62. The centering springs now rotate the lever 61 about the fulcrum point 73 in a counterclockwise direction and thereby reduce the amount of the correction previously made so that the final correction is proportional to the amount that the nut has been displaced along the screw.

It will thus be seen that the system in the modification of Fig. 2, like that of Fig. 1, provides both a rather large temporary correction for the positional relationship of the strip and the cutting knife and a small relatively permanent correction for the relative speeds of the strip and the knife.

If the strip and the knife had been out of register in the opposite sense of that assumed in connection with the above description of the operation of the modification to Fig. 2, the contactor 70 would have been energized and the relative space and relative speed corrections between the knife and the strip would have been made in the opposite sense to those above described.

Although in accordance with the provisions of the patent statutes this invention is described as embodied in concrete form, it will be understood that the apparatus and connections shown and described are merely illustrative and that the invention is not limited thereto since alterations and modifications will readily suggest themselves to persons skilled in the art without departing from the true spirit of the invention or the scope of the annexed claims.

What I claim as new and desire to secure by Letters Patent of the United States is:

1. A control system for a device having an element operating on a strip of material and means for feeding the strip to said element comprising a variable speed connection for varying the relative speeds of said feeding means and said element, a member acting on said connection, means actuated by the strip for actuating said member to effect a large temporary correction of the relative speed of said strip and said element, and additional means for causing said member to re-

duce said correction to provide a small permanent correction.

2. A control for a device having an element operating on a strip of material and means for feeding the strip to said element comprising a variable speed transmission between said feeding means and element for varying the relative speeds of said feeding means and element, a movable lever operating on the speed changing member of said transmission, means actuated by the relative positions of the strip and element for effecting a movement of said lever to produce a large temporary correction of the relative speeds of said strip and said element, and means for actuating said lever to reduce said correction to provide a small permanent correction.

3. A control system for a device having an element operating on a strip of material and means for feeding the strip to said element comprising a variable speed driving connection between said feeding means and element for varying the relative speeds of said feeding means and element, a movable lever acting on said connection, means controlled by the relative positions of said strip and element for effecting a movement of said lever to effect a relatively large temporary correction in the relative speeds of said strip and element, and means for subsequently reducing the amount of movement of said lever thereby to provide a small relatively permanent change in the relative speeds of said element and strip.

4. A control system for a device having an element operating on a strip of material and means for feeding the strip to said element comprising a variable speed driving connection between said feeding means and element for varying the relative speeds of said feeding means and element, a lever acting on said variable speed correction and having a movable fulcrum, means actuated by the relative positions of said strip and element for actuating said lever to make a relatively large temporary correction for the positional relationship of said strip and element and means providing movement of said fulcrum to reduce said correction.

5. A control system for a device having an element operating on a strip of material and means for feeding the strip to said element comprising driving means for said feeding means and element, a variable speed driving connection between said feeding means and element for varying the relative speeds thereof, a lever acting on said connection and having a movable fulcrum, means controlled by the relative positions of said strip and element for actuating said lever to provide a relatively large temporary correction for the positional relationship of said strip and element and centering springs for effecting movement of said fulcrum to reduce said correction to provide a final correction for the relative speeds of said strip and element, and a time delay device for retarding the movement of said fulcrum.

6. A control system for a device having an element operating on a strip of material and means for feeding the strip to said element comprising an electric motor for driving said feeding means and element, a variable speed driving connection between said feeding means and element for varying the relative speeds thereof, a lever acting on said connection and having a movable fulcrum, light sensitive means actuated by said strip and means controlled thereby for moving said lever to effect a relatively large temporary correction for the positional relationship of said strip and element and means for moving said fulcrum

to reduce the amount of movement of said lever and to provide a correction for the relative speeds of said strip and element.

7. A control system for a device having an element operating on a strip of material and means for feeding the strip to said element comprising an electric motor for driving said element and feeding means, a variable speed driving connection between said feeding means and element, a lever operating on said connection, said lever having a movable fulcrum, an electric motor for moving said lever, means controlled by the relative positions of said strip and element for causing said motor to move said lever to provide a relatively large temporary correction for the positional relationship of said strip and element, centering spring means for moving said fulcrum to reduce the movement of said lever to provide a reduced correction for the relative speeds of said strip and element, and a dashpot for controlling the rate of movement of said fulcrum.

8. A control system for a device having an element operating on a strip of material and means for feeding the strip to said element comprising an electric motor for driving said feeding means and element, a variable speed driving connection between said feeding means and element for varying the relative speeds thereof, a lever operating on said connection, a solenoid acting on said lever, a motor for actuating said lever, means controlled by the relative positions of said strip and element for energizing said solenoid and said motor to move said lever about its fulcrum to provide a correction for the positional relationship of said strip and element, a time element device for deenergizing said solenoid after a predetermined interval of time, and spring means for reducing the movement of said lever to provide a correction for the speed relationship of said strip and element.

DAVID R. SHOULTS. 20
